UNITED STATES PATENT OFFICE.

ROBERT J. BURNS, OF AVON, MASSACHUSETTS, ASSIGNOR TO UNITED SHOE MACHINERY COMPANY, OF PATERSON, NEW JERSEY, A CORPORATION OF NEW JERSEY.

CEMENTING-MACHINE.

1,087,272.

Specification of Letters Patent. Patented Feb. 17, 1914.

Application filed December 2, 1904. Serial No. 235,261.

To all whom it may concern:

Be it known that I, ROBERT J. BURNS, a citizen of the United States, residing at Avon, in the county of Norfolk and Commonwealth of Massachusetts, have invented 5 certain Improvements in Cementing-Machines, of which the following description, in connection with the accompanying drawings, is a specification, like reference characters on the drawings indicating like parts in 10 the several figures.

This invention relates to machines for applying cement or other liquid material to stock and particularly to machines for applying cement to shoes.

The invention is herein shown as embodied in a machine adapted for coating the bottoms of Goodyear shoes with cement preparatory to the sole-laying operation, the 20 cement being employed for the purpose of holding the outersole temporarily on the shoe and for forming a tight joint between the outersole and the welt, inseam, and filling when the outersole has been attached 25 permanently by the usual line of stitches.

The machine comprises a reservoir from which the cement is delivered as needed to a cement-applying means, herein shown and referred to as a brush, but which may be any 30 other suitable device adapted to apply a coating of cement to the surface of the work. The cement commonly used includes as a solvent a volatile liquid, such as naphtha, and consequently the cement dries rapidly 35 and becomes thick and stiff when exposed to the atmosphere. On this account, for the reason that a small quantity only is required for each shoe, it is advantageous to discharge the cement intermittently on the 40 cement-applying brush and then to spread or distribute it over the working face of the brush. For the purpose of coating the welt, inseam, and filling of a shoe the brush must be of considerable width and an important 45 feature of the present invention consists in novel means for spreading the cement upon the cement-applying brush. As herein shown, the cement is delivered upon the brush in a stream near one edge of the 50 brush and means is provided for working the cement laterally over the width of the brush. The means for spreading the cement may be a bar, plate, or other suitable device

arranged in proximity to the face of the brush between the delivering means and the 55 work for guiding and working a portion of the cement delivered on or carried by the rotating brush across the face of the brush toward the opposite edge. This object preferably will be effected by arranging the 60 spreading means obliquely across the face of the brush whereby the cement will be urged across the brush toward the edge thereof engaged by the rear end of the 65 spreader, or the bristles which form the working face of the brush may be arranged in rows extending obliquely across the face of the brush and the spreader arranged at an angle to the length of the rows of bristles so that the cement will be worked along the 70 oblique rows of bristles toward one edge of the brush.

Cement of different brands and grades varies in thickness or consistency and a machine in which the spreader is arranged to 75 distribute properly one kind of cement sometimes will not under the same conditions distribute satisfactorily a different kind of cement. In view of this fact and because it is sometimes desirable to vary the relative 80 amounts of cement carried by different portions of the brush I preferably provide means for controlling the relative quantities of cement carried by different portions of the brush. This may be accomplished by 85 means arranged to engage the whole or a portion of the face of the brush for wiping or working more or less of the cement off from certain portions and, it may be, transferring said excess of cement to other 90 portions of the brush. I have herein provided a scraper arranged to engage the face of the brush and adjustable into different angular positions with relation to the axis of rotation of the brush whereby it may be made to 95 scrape the cement carried by the brush from either side of the brush toward the other side. This means for controlling the relative quantities of cement carried by different 100 portions of the brush is independent of the means for spreading or distributing the cement over the face of the brush, but of course said spreading means might be constructed and arranged to cause different 105 relative quantities of cement to be carried by different portions of the brush, or said

spreading means might be made adjustable for varying the relative quantities of cement which shall be applied to different portions of the brush face. I have herein shown one 5 means for adjusting the spreading bar for this purpose.

The filling material which is applied over the innersole between the inseams for building up this portion of the shoe bottom flush 10 with the top of the inseam is usually composed of ground cork, leather trimming, or other fine granular material mixed with cement to form a paste. This material requires to be in a soft condition when applied and it does not adhere with much firmness to the sole until it has stood for some time to allow the cement to set. A difficulty 15 has been experienced in cementing the bottoms of shoes while the filling is still soft, because the cement-applying means is liable to loosen the filling material from the inner-sole and strip it from the shoe. To overcome this difficulty I have provided a novel construction of cement-applying means 20 having an acting face one portion of which is soft and yielding and is adapted to coat the filling with cement without loosening the filling from the innersole, said acting face having another portion which is firmer and 25 well adapted for coating with cement the uneven surface of the inseam and welt. To this end the different portions of the acting face of the brush may be made of different materials, as, for example, the portion en- 30 gaging the filling may be made of fine, soft bristles, while the portion engaging the inseam and welt is made of stiffer bristles.

It is found in practice that the brush is liable to pick up loose particles of the filling 40 material, which, if allowed to accumulate upon the brush and be carried around with it, would interfere with the operation of the brush to an objectionable extent, and to overcome this difficulty I prefer to employ 45 means for engaging the brush in the rear of the point where the brush acts upon the work, said means serving to scrape or remove from the brush any particles of the filling or other foreign material which may 50 have been picked up from the work. The means for removing these particles is herein shown as a bar arranged to extend obliquely across the face of the brush in position to scrape or strip off any particles of filling 55 material which the brush has picked up from the work. This bar may be the bar or scraper before referred to as employed for controlling the relative quantities of cement carried by different portions of the brush, as 60 has been before described.

Other features of the invention, including details of construction and combinations of parts, will be hereinafter described and pointed out in the claims.

65 Figure 1 is an end elevation of a portion

of a cementing machine embodying the invention. Fig. 2 is a plan view of the mechanism shown in Fig. 1. Fig. 3 is a sectional view on the line 3—3 of Fig. 1. Fig. 4 is a rear elevation of said mechanism and shows 70 also a portion of the cement-supplying means. Fig. 5 is a sectional view of a modified form of brush. Fig. 6 is a detail view of a modification. Fig. 7 shows means for adjusting the spreader, and Fig. 8 is a view 75 of a portion of the machine taken from the right as shown in Fig. 7.

The cement is supplied from a reservoir through a conduit 2 which is normally closed by a gate 4 adapted to be operated 80 manually by any suitable means, as, for example, by a connection with a foot treadle. The cement is delivered to the face of the cement-applying means, which is herein shown as a rotary brush 6 and referred to as 85 a brush, but which may be a roll or any other means adapted for the purpose. The brush is carried on a shaft 8 provided with a pulley 10 by which it may be continuously rotated. The brush is of a width suitable 90 for applying a coating of cement to the welt and inseam and preferably a portion of the filling of a Goodyear shoe, whereby the operator is enabled by passing each side of the shoe once under the brush to coat the entire welt and the inseam, and either the 95 whole or the marginal portion of the surface of the filling which occupies the middle portion of the shoe bottom between the inseams. The cement requires to be spread 100 over the face of the brush in order that the surface of the work engaged by the face of the brush may be properly coated, and I have for this purpose provided a spreader 12, herein referred to as a bar, but which 105 may be a rod, plate, or other suitable device, and which is shown as arranged across the face of the brush between the cement-delivering means and the place where the brush engages the work.

The cement is shown as delivered to the brush near the inner edge of the acting face of the brush and the spreader is arranged for working and guiding the cement across the face of the brush toward and preferably 115 to its outer edge, whereby the cement is distributed across the face of the brush. The arrangement of the spreader with relation to the brush may be varied according to the construction of the brush.

I have shown in Figs. 2, 3, and 4 a brush in which the bunches of bristles are arranged in rows extending obliquely from the inner edge of the brush downwardly and outwardly toward the outer edge of the brush 120 viewing Fig. 3. This arrangement of the bristles has the advantage, among others, that the periphery of the brush as a whole presents more nearly a true circle than is presented by a brush in which the bristles 125 130

are arranged in rows extending parallel with the axis and present intervening spaces tending to give the brush a polygonal shape. In said Fig. 3 I have shown the spreader as extending downwardly and outwardly substantially parallel with the rows of bristles. In this arrangement the outer end of the spreader is lower than the inner end with which cement delivered to the brush first comes in contact, and the cement is therefore worked and guided downwardly along the spreader and across the face of the brush, being impelled by gravity in that direction.

5 In Fig. 5 I have shown a section of a brush in which the bunches of bristles are arranged in rows parallel with the axis of rotation of the brush and in this figure the spreader is located at an angle to the rows 10 of bristles and therefore at an angle to the axis of rotation of the brush. With this arrangement the spreader will work the cement delivered to the brush laterally along the row of bristles from the end of the row 25 which first engages the spreader toward the opposite end of the row.

In Fig. 6, and in full lines in Fig. 7, I have shown both the rows of bristles and the spreader as extending obliquely across the face of the brush, the spreader, however, being arranged at an angle to the rows of bristles. A brush having its rows of bristles arranged obliquely presents, as has been explained, a surface which closely approximates that of a cylinder so that the spreader coöperates with it more satisfactorily for that reason. Aside, however, from the cylindrical surface presented the arrangement of oblique rows of bristles with a spreader 40 which is oblique to them serves to maintain the cement on the tufts on each row rather than to cause it to be forced in between the rows. Considering Fig. 4, for example, it will be evident that the cement deposited 45 upon the inner tufts of any given row of bristles will strike the obliquely arranged spreader before the remaining tufts pass beneath it so that the cement will tend to be spread over the tops of the tufts.

50 In the following description and in the claims the term "oblique" as applied to the cement spreader and to the scraper, which is hereinafter described, will be used to designate either an angular relation to the axis of 55 rotation of the brush or an angular relation to the rows of bristles which form the working face of the brush.

The spreader is shown in Figs. 1, 2, and 3 as projecting upwardly and laterally from a plate 16, said plate being located adjacent to the side of the brush so that as the cement works along the spreader toward its lower end the plate will constitute an abutment or dam for holding the cement and preventing 65 it from dripping off from the lower end of

the spreader. The upper end of the spreader may be supported by a second plate 18, as shown in Fig. 3, and in the illustrated embodiment of the invention the plates 16 and 18 are connected at their lower sides 70 and constitute a frame for supporting a plate 20 which is adjustable toward and from the periphery of the brush by means of a hand screw 22. The plate 20 may be employed if desired as a doctor for regulating the quantity of cement carried on the periphery of the brush. In case the brush becomes too heavily loaded the superfluous cement will be temporarily removed by the doctor and will pile up between the end of 75 the doctor and the periphery of the brush, as shown in Fig. 1, until a portion of the cement carried by the brush has been transferred to the work. The frame, comprising the side walls 16 and 18, is adjustably attached to a bracket 24 projecting from the machine frame, as shown in Fig. 2, and may be moved for placing the spreader at different distances from the brush.

That portion of the surface of the work 90 formed by the welt and inseam presents an irregular face, as indicated in Fig. 4, and in order to coat properly this irregular face it is necessary to employ in a cement-applying brush bristles of considerable stiffness 95 which will enter the depressions in the work. It is the practice, however, to cement shoe bottoms shortly after the filling material has been applied and before it has become sufficiently set to adhere firmly to the innersole. 100 In view of these facts I preferably employ a cement-applying brush having a portion for engaging the filling which is softer and more flexible than the portion which engages the inseam and welt and which is, 105 therefore, less liable to loosen or strip the filling from the innersole. Viewing Fig. 4 the left-hand side of the brush is the softer portion for engaging the filling material, while the right-hand side of the brush is 110 stiffer for engaging the uneven surface of the inseam and welt. Preferably the portion of the brush which engages the filling material is composed of relatively soft, flexible bristles, while the portion of the brush 115 which engages the welt and inseam is formed of coarser and stiffer bristles. In Fig. 5 is shown a brush comprising a tapering or cone-shaped hub 141, the base or larger end of which carries the bristles for 120 engaging the welt and inseam, while the end having the smaller diameter carries the bristles for engaging the filling.

It is found in practice that the brush loosens from this filling material some particles which are carried around by the brush 125 and it is desirable to provide means for removing these particles from the working face of the brush. For this purpose I have provided a bar or plate 30 arranged ob-

- liquely across the face of the brush in position to strip or scrape from the brush any particles which have been picked up from the work. The scraper is shown long enough 5 to act on the whole width of the brush, but it might be made shorter and act only on the portion of the brush which engages the filling material. The scraper is provided with a shank or bar 32 secured by a binding 10 screw 34 in a clamp 36. The scraper is preferably located at the rear of the brush and it may be moved toward and from the periphery of the brush and secured in adjusted position by the binding screw 34.
- 15 The different brands and grades of commercial cement vary in thickness or consistency, and it is found that such different kinds of cement are not distributed uniformly by a spreader occupying any given 20 position with relation to the brush. Also it is sometimes desirable when using the same kind of cement to apply a thicker coating to one portion of the work than to another, and I have therefore provided means for controlling the relative quantities of cement carried by different portions of the brush. The bar or plate 30, above described as being 25 adapted to scrape off particles of filling material which may adhere to the brush, may be employed if desired for controlling the relative amounts of cement carried by different portions of the face of the brush by adjusting said bar or plate into proper contact 30 with the brush and into different angular positions with relation to the face of the brush. By adjusting it into the lower position shown in dotted lines in Fig. 4 it will 35 wipe the cement from the right-hand portion of the brush viewing said figure and guide or work it toward the left-hand or 40 outer edge of the brush, thereby increasing the relative quantity of cement which will be applied to the filling material; and by adjusting the scraper into the upper position 45 shown in dotted lines in Fig. 4 it will wipe the cement from the left-hand portion of the brush and guide and work it toward the right-hand or inner side of the brush, thereby increasing the amount of cement which 50 will be applied to the welt and inseam.
- It is to be noted that the bar or plate 30 constitutes means independent of the spreading means for controlling the quantity of cement carried by different portions of the 55 face of the brush. In Fig. 7 I have shown the spreader 121 to be arranged for adjustment into different angular positions with relation to the brush, and it will be obvious that by inclining the spreader more or less 60 or by changing its inclination toward one side or toward the other of the brush the distribution of the cement over the face of the brush may be controlled and the brush caused to apply to different portions of the

work the desired relative quantities of cement. The spreader is shown in Fig. 7 as having on one end a lug 40 which is received loosely in a socket in the wall 18. The opposite end of the spreader is reduced in size and has a square portion 42 which extends through and is guided in a slot 44 in the wall 16. The end portion of the spreader outside the wall 16 receives a plate 46 and a binding screw 48. By loosening the binding screw the spreader may be moved from the full line position shown in the figure toward either of the dotted line positions and so vary the distribution of the cement over the face of the brush. The plate 46 covers the slot in the wall 16 and prevents the escape of cement.

It is found in practice that small quantities of cement work from the hub of the brush onto the shaft 8 and find their way into the shaft bearing, thereby causing the 85 shaft to run hard. To overcome this difficulty I have provided the brush shaft with a collar 50 located between the shaft bearing and the brush hub and spaced away from each of these parts as shown. The collar 90 acts as a dam or wall to stop the cement from working along the shaft from the brush toward the bearing. Preferably the collar will be formed with a beveled face on the side adjacent to the brush for more effectively guarding against the passage of cement beyond the collar.

In the use of the invention the brush is preferably rotated continuously and the work is supported in the hand of the operator. The gate is opened to permit the cement to flow on the brush and be spread or distributed over the face of the brush as the latter rotates in contact with the spreader. The shoe is presented, as indicated in Fig. 4, against the welt crease guide 52 and moved under the brush to cause the bottom of the shoe to be coated from one end to the other, the cement being applied first on one side of the shoe bottom and then on the other. 105 If the desired relative quantities of cement are not being applied to the filling material and to the welt and inseam, the angular position of the bar or plate 30 with relation to the face of the brush may be changed or the 110 spreader may be adjusted to cause more or less of the cement to be carried by either side of the brush.

It is sometimes desired to cement the bottom of the shoe before the filling material 120 is applied between the inseams and the machine is used in the same way for this purpose, the only difference being that cement is applied to the face of the inner sole instead of being applied to the filling material. 125

While for convenience I have described my invention as embodied in a machine for applying cement and have in the specifica-

tion and claims referred to the material used in such a machine as cement, it should be understood that my invention is not limited to a machine for applying cement, but that it is applicable to machines for applying other similar materials, and therefore whenever the word cement occurs in the specification or claims it should, where the context permits, be construed as meaning cement, semi-fluid, or viscous material.

Having explained the nature of my invention and fully described a construction embodying the same, I desire to claim as new and secure by Letters Patent of the United States:

1. In a machine of the class described, a cement-applying brush, and means for delivering cement to the brush, combined with a frame comprising side walls embracing a portion of the brush, a bar movably supported by said side walls and adapted to extend across the face of the brush for spreading the cement over the brush, and means for securing said bar to the side walls in different angular positions with relation to the brush.

2. In a machine of the class described, a cement-applying brush and means for supplying cement to the brush, combined with a frame comprising side walls embracing a portion of the brush, a bar supported for pivotal movement in one side wall and extending obliquely across the face of the brush and through a slot in the other side wall, and means for securing the bar in adjusted position in the slotted side wall.

3. In a machine of the class described, a cement-applying brush, means for supplying cement to the brush, a cement spreader supported for pivotal movement at one end of the brush and having a reduced portion at its other end, a support for said latter end of the spreader having a slot through which the reduced portion extends, a plate mounted on said reduced portion to cover the slot in the support, and means for securing the bar and plate in adjusted position.

4. In a machine of the class described, a cement-applying brush, means for supplying cement to the brush, a flattened bar arranged obliquely across the face of the brush and adapted to contact therewith, said bar being supported for pivotal movement at one end and having at its opposite end a non-cylindrical portion, a support provided with a slot shaped to fit said non-cylindrical portion and prevent the bar from turning, and means for securing said bar in different adjusted positions in the slotted support to vary its inclination with relation to the face of the brush.

5. In a machine of the class described, a cement-applying brush, means for delivering cement to the brush, and a spreader arranged

across the face of the brush and adapted to contact therewith, said machine having provision for permitting adjustment of the spreader to incline it toward either end of the brush.

6. A cementing machine having in combination a brush, means for supplying cement to said brush, a non-rotary scraper comprising a shank and a scraping member fast to said shank, and means whereby said shank may be adjusted angularly about its axis.

7. In a machine of the class described, a cement-applying brush, means for supplying cement, and means for distributing cement over the brush comprising members extending across the face of the brush in contact therewith at opposite sides of the brush, said distributing means being constructed and arranged to permit said members to be adjusted relatively for working the cement more or less across the face of the brush.

8. In a machine of the class described, a cement-applying brush, means for supplying cement, and means for distributing cement over the brush comprising two bars extending across the face of the brush at opposite sides of the cement-applying line thereof and each mounted for adjustment to engage the brush obliquely for working cement across the face of the brush.

9. In a cement-applying machine, the combination with means for supplying cement, of a rotary member having a peripheral cement-carrying face for applying the cement to the work, and a spreader for engaging the cement-carrying face and constructed and arranged for adjustment to work the cement toward either one or the other edge of said face.

10. In a cement-applying machine, the combination with means for supplying cement, of a rotary member having a peripheral cement-carrying face for applying cement to the work, and a scraper 30 pivotally supported by the stem 32 adjacent to one edge of the cement-carrying face and arranged for adjustment about said pivotal support in a plane substantially tangential to the cement-carrying face whereby the scraper may be positioned obliquely to the axis of the rotary member with the outer end at different distances from said face.

11. In a cement-applying machine, the combination with means for supplying cement, of a rotary member having a peripheral cement-carrying face for applying the cement to the work, and a bar pivotally supported adjacent to one edge of the cement-carrying face and arranged for adjustment whereby the end opposite the pivot is positioned at different distances from said face.

12. A machine of the class described having a rotary brush and means for supplying cement thereto in combination with a frame comprising side walls embracing a portion of the brush, means for adjustably fastening said frame to the head of the machine, an adjustable bottom carried by said frame and means for adjusting said bottom toward and from the periphery of

the brush to control the amount of cement delivered to the work.

In testimony whereof I have signed my name to this specification in the presence of two subscribing witnesses.

ROBERT J. BURNS.
